(57) **CLAIM**

The ornamental design for a front grill and lights assembly, as shown and described.

DESCRIPTION

FIG. 1 is a top front left perspective view of a front grill and lights assembly showing our new design.

FIG. 2 is a front view thereof.

FIG. 3 is a left side view thereof.

FIG. 4 is a right side view thereof; and,

FIG. 5 is a bottom view thereof.

The broken line showing of a hood is included for the purpose of illustrating environmental structure only and forms no part of the claimed design.
